UNITED STATES PATENT OFFICE.

CHARLES DOERING, JR., OF OAK PARK, ILLINOIS.

DESIGN FOR A CASING FOR BEVERAGE-DISPENSING DEVICES.

48,171.

Specification for Design.

Patented Nov. 23, 1915.

Application filed March 25, 1915. Serial No. 17,064. Term of patent 7 years.

To all whom it may concern:

Be it known that I, CHARLES DOERING, Jr., citizen of the United States, residing at Oak Park, in the county of Cook and State of Illinois, have invented a new, original, and ornamental Design for a Casing for Beverage-Dispensing Devices, of which the following is a specification, reference being had to the accompanying drawing, forming a part thereof.

The drawing shows a perspective view of a casing, for a beverage dispensing device, embodying my design.

I claim:

The ornamental design for a casing for a beverage dispensing device as shown.

CHARLES DOERING, JR.
